UNITED STATES PATENT OFFICE

2,570,595

JET-PROPELLED VESSEL

Frederick B. Romero, Washington, D. C.

Application September 22, 1947, Serial No. 775,442

3 Claims. (Cl. 114—56)

1

This invention relates to boats and vessels, especially of the type wherein a portion of the length of the craft is made with a center channel and rearwardly is made with two water jet tubes, which at their forward ends open within the vessel to fit a bushing mechanism of application of Ser. No. 648,802, filed February 14, 1946; and also open downwardly through the craft's bottom to admit water which is forced rearwardly through the said jet tubes, which open through the craft's stern plates. Moreover, this application is a continuation-in-part of application Serial Number 643,981, filed January 29, 1946, now Patent No. 2,550,298, dated April 24, 1951.

Objects of the present invention include a boat or vessel with jet tubes of the type set forth wherein the jet tubes are supported close to the craft's bottom and equidistant from the longitudinal centerline and occupy approximately one-third of the craft's total length, and thereby offer potential jet or jet driving force of an unusually great power. A further object of the invention is generally to improve the construction of boats and vessels with water jet drive systems of the type herewith set forth.

The herewith enclosed drawing consists of three illustrative figures wherein the same structural parts are indicated by the same number.

Fig. 1 is an elevation stern view of the water craft, boat, or vessel.

Fig. 2 is a side elevation partially in section of the water craft, boat or vessel.

Fig. 3 is a bottom plan view of the water craft, boat, or vessel.

In this construction illustrated in Figs. 1, 2, and 3, as applied to a water jet propelled water craft, to which the invention is more particularly intended, the water craft is comprised of the upper deck 1, the shell 2, which includes the stern plates 3, 4, 5, and 6, and center channel plates 7 and 17, the central keels 9, the bilge keels 8, the forward center keels 18 and 21, the platform deck 19, the five transverse flat-bar strength and stabilizing members 10, the rudder stock under-support 11, the rudder 13, the rudder stock 14, the jet tubes 12, with their forward end bottom openings 20, and their forward end bushing apertures 16, which become occupied by the bushing mechanism revealed in application of Ser. No. 648,802, filed February 14, 1946.

The boat's deck and shell plates are adequately supported by frame members. All lines and points of structural securement are bonded by welding. The boat's center channel, it will be noticed occupies the rearward approximate two-thirds of

2

the craft's total length, and forwardly the channel's top plate 17, curves downwardly and forwardly to become contiguous with the forward bottom keel 21. The medial surfaces of the channel's side plates 7, are coextensive with the medial surfaces of the central keels 9, the lateral surfaces of said central keels meet the craft's bottom shell along a line at a higher elevation than the craft's lowermost bottom shell, thereby forming a longitudinally extensive inverted somewhat V-shaped space along the craft's bottom, which when filled with water as occurs when the water craft is afloat, provides a transverse stabilizing effect. Further stability is provided by five transverse flat-bar members 10, extending between the lateral lines of lowest elevation along the craft's bottom and piercing the central keels 9, with which they are made continuous by welding. These five flat-bar members 10, provide not only transverse stability but also longitudinal stability preventing quick and much pitching motion of the craft on rough surfaced water. The central keels 9 and the bilge keels 8 provide transverse stability, preventing quick and much rolling motion of the craft on rough surfaced water.

The two jet tubes 12 are properly supported and welded to the inside of the craft's frame and shell structure, and occupy the rearward approximate one-third of the vessel's total length, and they open as shown through the craft's bottom, formed by apertures 20, in Fig. 3. In Figs. 1, 2, and 3, stern plates 5, it will be noticed, provide a flared or diverging rear end in the center channel, and thereby providing adequate space for movement of the rudder 13. The craft's stern is completed by transverse stern plates 3, 4, and 6.

Forwardly, the center keel 18, together with other frame members provides adequate shell sustaining strength. The platform deck 19, is properly supported and provides a top for inner bottom tanks and a support for vessel powering equipment. In vessels of transoceanic size a plurality of decks are provided with proper means of support and are made with properly placed hatches, watertight hatch covers and between deck stairways. And also in vessels of yacht size and larger, there are provided the commonly known superstructures such as the pilot house, bridge deck, etc., but such structures in themselves are not novel, and therefore, are not shown.

I claim:

1. In a water jet propelled vessel having a hull bottom formed to provide a pair of keels along

the turn of the bilge along each side of the hull and throughout the after two-thirds of the length of the hull, longitudinally directed V-shaped channels formed in the bottom of the hull substantially co-extensive in length with said bilge keels, parallel to said bilge keels along each side of the hull and adjacent the bilge keels, a pair of central keels parallel to said V-shaped channels, one of each pair forming the inboard side of one of said V-shaped channels and extending below the lowest point in the hull, a central channel between the central keels, the central channel substantially co-extensive in length with said bilge keels, the V-shaped channel and central keels, and a plurality of flat-bar members extending transversely of the open sides of the channels, the flat portions lying substantially in the same horizontal plane to afford increased stability; that improvement which comprises water jet propulsion tubes within the hull and along the V-shaped channels, said tubes terminating at their forward end two-thirds of the length of the vessel from the bow in openings in the V-shaped channels and terminating at their after end at the stern of the vessel and each side of

5

the central channel, said tubes formed to receive a propeller whereby water may be discharged adjacent the open end of the central channel.

2. A jet propelled vessel as claimed in claim 1 wherein the after sides of the central channel are formed to flare outwardly at the rear end of said channel.

3. A jet propelled vessel as claimed in claim 1 wherein the after ends of the tubes are formed to provide constricted portions.

FREDERICK B. ROMERO.
